(57) **CLAIM**

The ornamental design for a dual screen display, as shown and described.

DESCRIPTION

FIG. 1 is a front, top perspective view of a dual screen display, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1;

FIG. 10 is an enlarged view of detail "10" identified in FIG. 2;

FIG. 11 is an enlarged view of detail "11" identified in FIG. 2;

FIG. 12 is an enlarged view of detail "12" identified in FIG. 2; and,

FIG. 13 is another perspective view thereof, shown in an alternate position.

The even-dashed broken lines in the figures illustrate portions of the dual screen display that form no part of the claimed design. The dash-dot-dash broken lines in FIGS. 1, 2, 9, 10, 11 and 12 are for the purpose of illustrating the enlarged view indicators and form no part of the claimed design.
